UNITED STATES PATENT OFFICE.

MELVILLE H. BARKER, OF BOSTON, AND COMFORT A. ADAMS, OF CAMBRIDGE, MASSACHUSETTS, ASSIGNORS TO AMERICAN TOOL & MACHINE COMPANY, OF BOSTON, MASSACHUSETTS, A CORPORATION OF MASSACHUSETTS.

MEANS FOR DRIVING CENTRIFUGAL MACHINES.

1,146,767.

Specification of Letters Patent. Patented July 13, 1915.

Application filed April 18, 1910. Serial No. 556,088.

To all whom it may concern:

Be it known that we, MELVILLE H. BARKER and COMFORT A. ADAMS, citizens of the United States, and residents, respectively, of Boston, in the county of Suffolk and State of Massachusetts, and of Cambridge, in the county of Middlesex and State of Massachusetts, have invented certain new and useful Improvements in Means for Driving Centrifugal Machines, of which the following is a specification.

This invention relates to centrifugal machines and is intended to provide a simple and efficient means of braking or stopping said machines and further to provide such a combination with an electrically driven machine as shall make it impossible for the operator to apply the brake while the current is energizing the motor which drives the machine.

With these objects in view the invention comprises a novel arrangement and combination of brake with such a centrifugal machine and further consists in the combination with such a brake of an electric switch by which the control of the energizing circuit through the motor is maintained.

In the accompanying drawings we have illustrated the preferred form of embodying the principles of this invention.

In said drawings, Figure 1 is a side elevation partly in central section showing the brake mechanism applied to a direct-connected electrically driven centrifugal machine. Fig. 2 is a detail view in central vertical section showing the relation of parts of the brake mechanism. Fig. 3 is a plan view illustrating the relation of the two brake elements to each other. Fig. 4 is a front elevation showing the toggle lever connection for actuating the brake. Fig. 5 is a horizontal section through the coupling member. Fig. 6 is an elevation showing the interlocking brake lever and electric switch member.

In the practice of the invention according to the embodiment thereof illustrated in the drawings, we bolt a socketed bracket a' to the rigid I-beams a to form a support for the centrifugal machine. In this socketed bracket or hanger a' is mounted an

oscillatory sleeve b which has a spherical bearing in the socket and is provided with an internal shoulder b' upon which is carried a suitable anti-friction thrust bearing b^2 which serves to support the upper section c of the rotatable basket shaft.

The rotatable basket shaft is divided horizontally into two separable easily disconnected sections c c^2 , the basket c of the usual type being secured to the lower end of the lower section. The upper section terminates just below the lower end of the oscillatory sleeve b and the adjacent ends of the upper and lower sections are provided with enlarged heads to receive retaining bolts in order to detachably but rigidly couple the two shaft sections together. The enlarged head or flanged portion c' of the upper section is also screw-threaded as shown at c^4 to permit the attachment of the oil cup c^3 which surrounds the projecting lower end of the oscillatory sleeve b and also the exterior of the socketed member of the hanger a' . The shaft c has a lateral bearing against the interior bore of the lower part of the sleeve b and the oil is kept at such a level in the oil cup as to lubricate this lateral bearing as well as to immerse the thrust bearing at b^2 .

A brake wheel d , which is provided with a downwardly and inwardly extending flange portion d' , is clamped firmly between the adjacent heads of the upper and lower shaft sections by means of the retaining bolts so as to detachably but rigidly secure the same to the rotary shaft. For the purpose of radiating the heat generated by friction as rapidly as possible, the brake wheel is provided with external flanges or ribs d^2 . The non-rotating brake element comprises two brake shoes e carried by pivoted arms or levers e' which are supported by the vertical pivot post e^2 which passes through the perforated flanges e^3 formed at the rear of the brake arms. Each brake arm as shown is provided with two such perforated flanges e^3 so that the outer ends of the brake arms require no supporting means to hold them in horizontal position.

At their forward or outer ends the brake arms e' are socketed to receive the ball ends

of the toggle arms e^4 , one of which is made extensible by means of a screw-threaded shank e^5 which is held in an internal screw-threaded socket member. The adjacent ends 5 of the toggle arms e^4 are engaged by a vertically movable rod e^6 , which by its downward movement thrusts apart the free ends of the arms e^4 so as to exert a powerful pressure of the brake shoe against the interior 10 face of the brake wheel e . When the rod e^6 is lifted, the toggle members are flexed and the contractile spring e^7 serves to draw the brake shoes out of engagement with the brake wheel.

15 The means shown for actuating the toggle rod e^6 comprise the link member e^8 pivotally connected with the arm e^9 secured to the rock shaft e^{10} and to the latter is rigidly fastened the hand-operated brake lever e^{11} 20 which is preferably provided with an adjustable stop screw e^{12} adapted to engage against the lower rib of the I-beam α or any suitable stationary member, so as to limit the downward movement of the brake lever 25 in order to prevent the toggle from being forced beyond the point of dead center.

When the brake is employed on an electrically driven machine, we use also a switch comprising a disk member or plate d to 30 which is secured a switch arm d' , a portion of which d^2 lies in the path of the adjacent brake lever e^{11} . The switch plate or disk d carries an insulating plate d^3 and a pair of electrically connected contact fingers d^4 35 which are adapted to register with and engage a corresponding pair of contact fingers d^5 located on the insulating plate d^3 , so that when the disk d is rotated in a contra-clockwise direction, the circuit through the electro-magnet d^7 is closed but when it is rotated in a clockwise direction said circuit is 40 broken. The closing of the circuit through the magnet d^7 acts upon a solenoid switch member, conventionally shown at d^8 , to close 45 the contacts d^9 of the main circuit which passes through the electric motor to energize the same in order to drive the machine. The motor f is conventionally shown in Fig. 1 and the motor shaft f' thereof is co- 50 axially arranged with reference to the solid basket shaft c and is connected to the upper end of the basket shaft c by means of a flexible coupling connection comprising the two members g g' which are flexibly connected to 55 each other by means of a peculiar arrangement of belts g^2 which serves to transmit motion from the driving member g to the driven member g' , while allowing the basket shaft to oscillate freely with reference to the 60 motor shaft f' without bringing lateral strain upon the bearings of the motor shaft. This result is secured by carrying a long bight or loop of the driving belt through 65 openings formed in the outer driving mem-

ber g , the loop or bight being carried back 65 from this opening in a direction nearly parallel to the periphery of the outer member itself a sufficient distance to pass around a section or portion of the inner driven member g' . The other belt is formed into similar 70 open loops or bights extending in the reverse direction so as to prevent back-lash while allowing complete freedom of oscillation of the members g , g' within the limits necessary for the proper action of the machine. 75

The brake wheel is arranged in the horizontal plane of the center of oscillation of the sleeve and also in the plane of the rotary bearing, so that it has the minimum amount 80 of oscillation at the point where the braking strain is applied. By simply removing the coupling bolts which connect the upper and lower sections of the basket shaft, the brake wheel can be dropped clear of the rest 85 of the apparatus affording free access to the brake shoe members and to the oil cup which it normally surrounds.

In Fig. 6 the brake lever is shown at its lowermost position, at which point it acts to 90 set the brake shoes with the greatest force against the brake wheel, while in this position it is impossible to throw the electric switch d by reason of its engagement at d^2 with the brake lever. The raising of the 95 brake lever releases the brake and makes it possible to close the switch in order to energize the motor and start the machine in operation. If the brake be applied when the switch is in closed position, this same engagement serves to cause the rotation of the switch member d in order to separate the contacts at d^4 d^5 before the brake comes into action. When the brake is in inoperative position, the switch may be thrown in either 100 direction. The fixed stop a^{10} engaging the notched portion of the disk d serves to limit the extent of its rotation.

What we claim is:—

1. The combination with the gyratory 110 centrifugal shaft of an electrically driven motor, brake elements arranged to arrest the rotation of said shaft, an actuating lever for setting and releasing said brake mechanism, an electric switch and its actuating lever for controlling the admission of current to the motor, the brake lever and the switch lever being capable of independent movement and interlocking connections by which the switch is held in open position and 120 is moved to open position when the brake is set, substantially as described.

2. The combination of the suspended rotary centrifugal basket shaft, an electric motor for driving the same, brake mechanism 125 for arresting the movement of the shaft, an actuating lever for said brake mechanism, a partially rotatable switch element and its

lever arranged adjacent to said brake lever, the switch element and the brake lever being independently rotatable and being arranged so that the brake lever when in operative position obstructs the rotation of the switch member into operative position, substantially as described.

In witness whereof we have subscribed the above specification.

MELVILLE H. BARKER.
COMFORT A. ADAMS.
